(57) **ABSTRACT**

A dial for a timepiece includes a support and a mother-of-pearl sheet, the mother-of-pearl sheet having a front face and a rear face facing the support and on which a pattern has been printed. The mother-of-pearl sheet has a thickness between 50 μm and 100 μm so that the pattern printed on the rear face of the mother-of-pearl sheet appears transparently through the mother-of-pearl under normal conditions of illumination.

1

DIAL FOR A TIMEPIECE AND METHOD
FOR MANUFACTURING THE SAME

FIELD OF THE INVENTION

The invention relates to a dial for a timepiece comprising a support and a mother-of-pearl sheet, the mother-of-pearl sheet having a front face and a rear face facing said support and on which a pattern has been printed. The invention also relates to a method for manufacturing such a dial, and to a timepiece comprising such a dial.

BACKGROUND OF THE INVENTION

A dial of this type is described, for example, in Swiss Patent No. CH 697 210. In this document, the pattern is formed by phosphorescent, fluorescent or luminescent light elements in order to form an image that is visible in the dark but invisible under normal conditions of illumination. To achieve this, the light elements can be applied to the rear face of the mother-of-pearl or to the substrate or be deposited in blind cavities made in the mother-of-pearl or in the substrate. The recommended thickness for the mother-of-pearl sheet is 0.4 mm. This thickness is necessary in order to make the blind cavities. Further, the mother-of-pearl sheet must be sufficiently thick so that the phosphorescent pigment layer does not appear transparently through the mother-of-pearl in daylight, in normal conditions of illumination. This thickness of mother-of-pearl gives the dial a significant thickness so that it is not possible to make ultra-thin dials for the production of ultra-thin watches.

SUMMARY OF THE INVENTION

It is an object of the present invention to overcome the aforementioned drawbacks by proposing a mother-of-pearl dial and the method for manufacturing the same making it possible to produce an ultra-thin dial and an ultra-thin timepiece, notably a watch, comprising such a dial, without impairing the characteristic appearance of the mother-of-pearl.

To this end, the invention relates to a dial for a timepiece comprising a support and a mother-of-pearl sheet, the mother-of-pearl sheet having a front face and a rear face facing said support and on which a pattern has been printed.

According to the invention, the mother-of-pearl sheet has a thickness of between 50 μm and 100 μm so that the pattern printed on the rear face of the mother-of-pearl sheet appears transparently through the mother-of-pearl under normal conditions of illumination.

Thus, there is obtained a mother-of-pearl dial decorated with an ultra-thin pattern while still preserving the iridescent nature of the mother-of-pearl and smooth appearance of the mother-of-pearl on the front face, visible to a user.

BRIEF DESCRIPTION OF THE DRAWINGS

Other features and advantages will appear clearly from the following description, given by way of non-limiting illustration, with reference to the annexed drawings, in which:

FIG. 1 is a top view of a dial according to the invention; and

FIG. 2 is a sectional view along axis AA of FIG. 1.

DETAILED DESCRIPTION OF PREFERRED
EMBODIMENTS

Referring to FIG. 1, dial 1 for a timepiece comprises a support 2 and a mother-of-pearl sheet 3.

2

Preferably, support 2 is metallic. It is, for example, made from a sheet of brass.

The mother-of-pearl sheet has a front face 3a, corresponding to the side visible to the user, and a rear face 3b, positioned facing support 2 and on which a pattern 4 has been printed.

A metal ring 6, preferably made of brass, is provided on the peripheral edge of mother-of-pearl sheet 3 to define the contours of dial 1. This metal ring 6 can, for example, have a thickness on the order of 700 μm to 900 μm , for example 800 μm .

According to the present invention, the mother-of-pearl sheet has a thickness of between 50 μm and 300 μm so that the pattern printed on the rear face of the mother-of-pearl appears transparently through the mother-of-pearl under normal conditions of illumination, particularly in oblique light. Preferably, the mother-of-pearl sheet has a thickness comprised between 50 μm and 250 μm , preferably between 100 μm and 200 μm , preferably between 120 μm and 180 μm , more preferably between 130 μm and 170 μm , and still more preferably between 140 μm and 160 μm . For example, the thickness of the mother-of-pearl sheet is approximately 150 μm . Such a thickness of the mother-of-pearl sheet is a compromise found by the Applicant making it possible, on the one hand, to preserve the necessary transparency for the pattern printed on the rear face of the mother-of-pearl to appear transparently through the mother-of-pearl under normal conditions of illumination, and on the other hand, to avoid breaking the mother-of-pearl sheet, particularly when printing the pattern, due to excessive fragility.

Advantageously, metal support 2 can, for example, have a thickness on the order of 200 μm to 250 μm , so that the dial has, for example, a total ultra-thin thickness of 350 μm to 400 μm .

Printed pattern 4 can be any type of pattern. Preferably, the printed pattern is formed by a set of lines of different widths, creating the appearance of a structure. For example, the pattern may represent the veins and structure of a leaf.

Preferably, the mother-of-pearl used is natural mother-of-pearl.

Advantageously, the mother-of-pearl can be coloured.

The method for manufacturing such a dial includes the steps of:

- 45 a) providing a support 2, preferably metallic, for example made of brass
- b) providing a mother-of-pearl sheet 3 having a thickness comprised between 50 μm and 300 μm , preferably between 50 μm and 250 μm , preferably comprised between 100 μm and 200 μm , more preferably between 120 μm and 180 μm , more preferably between 130 μm and 170 μm , and still more preferably between 140 μm and 160 μm
- c) printing a pattern 4 on the rear face 3b of the mother-of-pearl sheet
- d) assembling the printed mother-of-pearl sheet 3 obtained in step c) on support 2.

The method also comprises a step of assembling the metal ring 6 on the peripheral edge of mother-of-pearl sheet 3.

In steps a) and b), support 2, mother-of-pearl sheet 3 and ring 6 are cut and prepared to have the desired shape and dimensions of the dial, and the thicknesses according to the invention. Orifices 8 are also made in support 2 and mother-of-pearl sheet 3 for the passage of the arbor of the hands.

65 According to step c), a pattern 4 is printed on rear face 3b of the mother-of-pearl sheet by means of an ink deposited according to a method chosen from the group including silk

3

screen printing, photolithography and inkjet printing. Silk screen printing is particularly preferred.

Advantageously, the thickness of the deposited ink layer is comprised between 10 μm and 40 μm , preferably between 20 μm and 30 μm . The ink used is a standard ink.

Preferably, the printing method is implemented to print a pattern formed by a set of lines of different widths to create the appearance of a structure.

Further, the method of the invention can comprise a step e) of tinting the mother-of-pearl before step c) of printing the pattern.

Once the printed mother-of-pearl sheet 3 is obtained in step c) and ring 6 is assembled on support 2 to form dial 1, the front face 3a of the mother-of-pearl sheet can be polished to obtain a smooth front face. Mother of pearl sheet 3 is then protected by a sapphire crystal (not represented). Indices or other decorative elements can be deposited on the sapphire crystal or on mother-of-pearl sheet 3.

The present invention also concerns a timepiece comprising a dial as described above. The invention makes it possible to obtain an ultra-thin dial, made of mother-of-pearl decorated with a pattern, while preserving the iridescent nature of the mother-of-pearl and the smooth appearance of the mother-of-pearl on the front face. The pattern appears more discreet, more delicate and more elegant transparently through the mother-of-pearl. The invention also makes it possible to obtain an ultra-thin timepiece, and particularly an ultra-thin watch, because of the use of an ultra-thin dial.

The invention claimed is:

1. A dial for a timepiece comprising:
a support;
a mother-of-pearl sheet, the mother-of-pearl sheet having a front face and a rear face facing said support and on which a pattern has been printed;
a sapphire crystal positioned on the front face of the mother-of-pearl sheet; and
a ring provided around a peripheral edge of the mother-of-pearl sheet,
wherein the mother-of-pearl sheet has a thickness of between 140 μm and 160 μm so that the pattern printed

4

on the rear face of the mother-of-pearl sheet appears transparently through the mother-of-pearl under normal conditions of illumination,
wherein the printed pattern is formed by a set of lines of different widths,

wherein the ring has a thickness from 700 μm to 900 μm , and
wherein the support has a thickness from 350 μm to 400 μm .

2. The dial according to claim 1, wherein the mother-of-pearl is colored.

3. The dial according to claim 1, wherein the support is metallic.

4. The method for manufacturing a dial for a timepiece comprising a support and a mother-of-pearl sheet according to claim 1, wherein the method includes the steps of:

- a) providing a support
- b) providing the mother-of-pearl sheet having a thickness comprised between 140 μm and 160 μm
- c) printing a pattern on the rear face of the mother-of-pearl sheet
- d) assembling the printed mother-of-pearl sheet obtained in step c) on the support.

5. The method according to claim 4, wherein the method also includes a step e) of tinting the mother-of-pearl before step c) of printing the pattern.

6. The method according to claim 4, wherein step c) of printing the pattern is achieved using an ink deposited in accordance with a method chosen from the group comprising silk screen printing, photolithography, and inkjet printing.

7. The method according to claim 4, wherein the support is metallic.

8. The method according to claim 6, wherein the ink is deposited in a layer with a thickness comprised between 10 μm and 40 μm .

9. A timepiece comprising a dial according to claim 1.
